UNITED STATES PATENT OFFICE

MARCUS C. HOPKINS, OF WASHINGTON, DISTRICT OF COLUMBIA, ASSIGNOR TO HOPKINS CORPORATION, OF JERSEY CITY, NEW JERSEY, A CORPORATION OF DELAWARE

LOUD-SPEAKER

Application filed December 22, 1925. Serial No. 77,033.

The present invention relates to loud speakers suitable for use with radio receiving sets, or as announcers for telephone and like wired circuits. The principal object of the invention is to provide a highly efficient loud speaker capable of regenerating or reproducing sound waves directly in free air, without distortion as in a horn or other amplifying device, the sound so regenerated retaining substantially the same balance of high and low tones as the original sound from which the actuating force was derived.

To this end the improved loud speaker comprises a relatively light and stiff diaphragm or tympanum, preferably conical in shape, and a sound board or resonator having greater mass than that of the diaphragm. The connection between the diaphragm and the resonator or sound board is such that the diaphragm will respond to the relatively high frequencies and will efficiently reproduce the high tones or sounds, and the relatively low frequencies will be transmitted through said connection to the sound board so that it will respond to the relatively low frequencies and will efficiently reproduce them.

Several forms of loud speakers constructed in accordance with the invention are disclosed in the accompanying drawings, in which

Fig. 1 is a front view of a loud speaker especially designed for use in hotels, theatres, concert halls and similar places where a large volume of sound is desired;

Fig. 2 is a side elevation of the speaker shown in Fig. 1;

Fig. 3 is a rear view of the loud speaker shown in Fig. 1;

Fig. 4 is a vertical section taken on the line 4-4 of Fig. 3;

Fig. 5 is an enlarged detail vertical section of the central portion of the loud speaker showing the connection between the diaphragm and the sound board;

Fig. 6 is a front elevation of another type of loud speaker operating on the same principle as that shown in Fig. 1;

Fig. 7 is a top plan view of the loud speaker shown in Fig. 6;

Fig. 8 is a rear elevation of the speaker shown in Fig. 6;

Fig. 9 is a vertical section taken on the line 9-9 of Fig. 8.

Referring first to Figs. 1 to 5 inclusive, the loud speaker shown in these figures comprises a central conical diaphragm or tympanum 1 coupled to a vibratory external annular resonator or sound board 2 by means of a semi-flexible coupling, shown in Fig. 5. The conical diaphragm 1 is preferably made of cover paper cut and folded to shape and glued along a radial seam. Near the outer edge of the cone thus formed the paper is creased and then folded up to form a forwardly flaring brim 3 (Fig. 5). This brim naturally assumes an angle to the plane of the base equal to the angle between the radial elements of the cone and that base. The outer edge portion of the brim 3 is preferably glued to the inner circular edge of the resonator or sound board 2. For this purpose the inner circular edge of the sound board is tapered as shown at 4 and the outer edge portion of the brim 3 seats upon and is glued to the tapering surface thus formed. In gluing or cementing the brim to the beveled edge 4 it is important that a part of the brim be left free to form a hinge on which the cone may float. Thus with a brim $\frac{3}{4}$ " wide the cemented portion may have a width of $\frac{1}{4}$ of an inch more or less and the remainder of the brim may be left free to swing.

The resonator or sound board 2 is preferably made of wood. It can conveniently be made of 3-ply veneer as shown in Fig. 5 with the grain of the inner ply running transverse to the grain of the two outer plies. Fir and spruce may be used for this purpose with good results.

The vibratory actuating force is applied to the apex of the conical diaphragm by means of a rod or wire 5 which is adapted to be maintained in fixed relation with the diaphragm by means of a set screw 6. The rod 5 may be actuated by electromagnetic mechanism housed in the casing 7. The casing 7 may be attached to a support or spider 8 which in turn may be affixed to the resonator or sound board by means of wood screws 9.

While the loud speaker shown in Figs. 1 to 5 inclusive may be made of any desired size

within reasonable limits, it has been found that for concert work excellent results have been obtained by making the conical diaphragm approximately 17 inches in outside diameter and the resonator or sound board approximately 4 feet in outside diameter. The relatively large size of the loud speaker shown in Figs. 1 to 5 inclusive makes it desirable to suspend it by cords or chains which may be attached to any suitable part of the loud speaker, preferably the spider 8. The loud speaker may be suspended from the ceiling of a room, a bracket or any other supporting device.

15 The loud speaker shown in Figs. 6 to 9 inclusive is very similar in construction to that above described as it comprises a conical tympanum 1', a sounding board or resonator 2', a spider 8' for supporting the casing 7' of the electromagnetic actuating mechanism, and a forwardly flaring brim 3' on the cone which is attached to the inner edge of the sound board in the same manner as explained in connection with Figs. 1 to 5. The main difference between the speaker shown in Figs. 6 to 9 inclusive and that shown in the first five figures is that the sound board or resonator 2' is of smaller diameter than the sound board shown in the first five figures.

20 25 The conical diaphragm 1' may or may not be smaller than the conical diaphragm of the loud speaker of Figures 1 to 5. The reduction in overall size of the loud speaker shown in Figs. 6 to 9 inclusive makes it possible to support the speaker on a table or other horizontal surface and for this reason the sound board 2' is provided with suitable legs or cross pieces 10 glued or otherwise fastened to the sound board. The sound

25 30 35 40 45 50 55 60 65 70 75 80 85 90 95 100 105 110 115 120 125 130

board may be provided with an opening 11 to provide a hand grip for moving the loud speaker from one place to another. In constructing a loud speaker of the type shown in Figs. 6 to 9 I have found that excellent results are obtained by making the cone 2' approximately 15½" in diameter and the sound board approximately 22" in diameter. This makes the transverse width of the annular sound board approximately 3½" but good results may be obtained by making the sound board of even less width than this or of even greater width than the sound board shown in Figs. 1 to 5 inclusive.

55 In both types of the speaker the conical diaphragm efficiently reproduces the higher tones and perhaps some of the intermediate tones while the resonator or sound board efficiently reproduces the lower or bass notes.

60 65 70 75 80 85 90 95 100 105 110 115 120 125 130

It will therefore be seen that the character of the flexible coupling between the conical diaphragm and the sound board is important as it should be flexible enough to permit the conical diaphragm to respond to the higher frequencies and it should be rigid enough to

transmit the lower frequencies to the sound board.

In a loud speaker constructed in accordance with the foregoing description, the regenerated or reproduced sound waves are substantially directly proportional both quantitatively and qualitatively to the actuating force and the sound so reproduced retains substantially the same balance of high and low tones as the original sound from which the actuating force was derived.

I claim:

1. A loud speaker comprising a central relatively light and stiff diaphragm, an external sound board of greater mass than the diaphragm, and a flexible coupling between the two adapted to permit the central diaphragm to respond to relatively high frequencies and adapted to transmit the relatively low frequencies to the sound board, the combined area of the diaphragm and the sound board being sufficient to impart directly to the surrounding air sound waves of clear audibility.

2. A loud speaker comprising a central conical diaphragm, an external sound board of greater mass than the diaphragm, and a flexible coupling between the two adapted to permit the conical diaphragm to respond to relatively high frequencies and adapted to transmit the relatively low frequencies to the sound board, the combined area of the conical diaphragm and the sound board being sufficient to impart directly to the surrounding air sound waves of clear audibility.

3. A loud speaker comprising a central conical diaphragm, an external sound board and a connection between the conical diaphragm and the sound board adapted to permit the central diaphragm to respond to relatively high frequencies and adapted to transmit the relatively low frequencies to the sound board, the combined area of the conical diaphragm and the sound board being sufficient to impart directly to the surrounding air sound waves of clear audibility.

4. A loud speaker comprising a central conical diaphragm, a wooden sound board providing an annular flange extending radially beyond the conical diaphragm and a connection between the conical diaphragm and the wooden sound board adapted to permit the conical diaphragm to respond to relatively high frequencies and adapted to transmit the relatively low frequencies to the wooden sound board, the combined area of the conical diaphragm and the sound board being sufficient to impart directly to the surrounding air sound waves of clear audibility.

5. A loud speaker comprising a central conical diaphragm having an integral forwardly flaring brim portion, and a wooden sound board providing a flange portion extending radially beyond the conical diaphragm, said forwardly flaring brim por-

- tion of the conical diaphragm being attached to the sound board.
6. A loud speaker comprising a conical diaphragm provided with a peripheral corrugation forming a hinge portion, and a sound board extending radially beyond the conical diaphragm, said hinge portion being secured to said sound board, and having flexibility sufficient to permit the conical diaphragm to respond to relatively high frequencies and having rigidity sufficient to cause transmission of the relatively low frequencies to the sound board, the combined area of the conical diaphragm and the sound board being sufficient to impart directly to the surrounding air sound waves of clear audibility.
7. A loud speaker comprising a sound board, and a conical diaphragm flexibly connected thereto so that a portion of the sound board extends radially beyond the conical diaphragm, the flexible connection between the conical diaphragm and the sound board having flexibility sufficient to permit the conical diaphragm to respond to relatively high frequencies and having rigidity sufficient to cause transmission of the relatively low frequencies to the sound board, the combined area of the conical diaphragm and the sound board being sufficient to impart directly to the surrounding air sound waves of clear audibility.
8. A loud speaker comprising a central conical diaphragm made of paper, an external sound board made of wood, and a flexible connection between the two having flexibility sufficient to permit the conical diaphragm to respond to relatively high frequencies and having a rigidity sufficient to cause transmission of the relatively low frequencies to the sound board, the combined area of the conical diaphragm and the sound board being sufficient to impart directly to the surrounding air sound waves of clear audibility requiring no sound box or megaphone amplification.
9. A loud speaker comprising a sound board having a central opening, a conical diaphragm mounted in said opening, actuating means for the conical diaphragm and means for supporting said actuating means comprising a support attached to the sound board and spanning the central opening thereof.
10. A loud speaker comprising an annular flat sound board having a circular central opening, a conical diaphragm having a circular periphery, said conical diaphragm being mounted in said opening, and a flexible coupling between the conical diaphragm and the sound board having flexibility sufficient to permit the conical diaphragm to respond to relatively high frequencies and having rigidity sufficient to cause transmission of relatively low frequencies to the sound board.
11. A loud speaker comprising an annular sound board having a central opening the edge portion of which is provided with a

tapering seat, and a conical diaphragm mounted in said opening said diaphragm having a forwardly flaring frusto-conical brim portion secured to the sound board on said tapering seat.

12. A loud speaker comprising a flat annular sound board made of wood, said sound board having a central opening the edge portion of which is provided with a tapering seat, and a fibrous conical diaphragm mounted in said opening and having an integral forwardly projecting brim portion, a part of said brim portion being attached to the sound board at said tapering seat.

13. A loud speaker comprising an annular sound board having a central opening, a conical diaphragm mounted in said opening, said sound board being provided with a tapering seat and the conical diaphragm being provided with a flexible brim portion secured to the sound board on said tapering seat.

14. A loud speaker comprising a sound board and a conical diaphragm, the sound board being provided with a tapering seat and the conical diaphragm being provided with a bent brim portion secured to the sound board on said tapering seat.

15. A loud speaker comprising a conical diaphragm, a sound board and a connection between the conical diaphragm and the sound board adapted to permit the conical diaphragm to respond to relatively high frequencies and adapted to transmit the relatively low frequencies to the sound board, the combined area of the diaphragm and the sound board being sufficient to impart directly to the surrounding air sound waves of clear audibility.

16. In a sound reproducing device, a cone and a sounding board connected thereto, said sounding board being freely and flexibly suspended, and means to set them in vibration.

17. In a sound reproducing device, the combination of a cone and a flat sounding board of substantial width, said sounding board being freely and flexibly suspended, and electric means for operating said cone and board.

18. A loud speaker comprising a cone and a plane vibratory unit freely and flexibly supported, a motor and means for mounting said unit and said motor operatively together.

19. A loud speaker including a freely suspended sounding board, a cone extending through said sounding board and fastened thereto, and means for actuating said sounding board and cone.

In testimony whereof I affix my signature.

MARCUS C. HOPKINS. 125
